UNITED STATES PATENT OFFICE.

CHARLES A. RUSSELL, OF PROVIDENCE, RHODE ISLAND.

BUTTON-BADGE FASTENER.

SPECIFICATION forming part of Letters Patent No. 729,671, dated June 2, 1903.

Application filed June 8, 1901. Serial No. 63,777. (No model.)

To all whom it may concern:

Be it known that I, CHARLES A. RUSSELL, a citizen of the United States, residing at Providence, in the county of Providence and State 5 of Rhode Island, have invented certain new and useful Improvements in Button-Badge Fasteners, of which the following is a specification, reference being had therein to the accompanying drawings.

10 Like letters indicate like parts.

Figure 1 is a front elevation of a button-badge provided with my improved fastening device. Fig. 2 is a diametrical section of my invention as seen on line xx of Fig. 1. Fig. 15 3 is a rear elevation of said invention with the fastening-slide in position when the badge is about to be inserted in the buttonhole of the garment. Fig. 4 is a rear elevation of a modified form of said invention with the 20 fastening-slide extended-in wearing position. Fig. 5 is a diametrical section of the same as seen on line yy of Fig. 4.

My invention relates to the fastening means of that class of badges having a shank which 25 passes through the buttonhole of a coat or other garment; and it consists of the novel construction and combination of the several parts, as hereinafter particularly described, and specifically set forth in the claims.

30 In the drawings, A is the button-badge, of any desired size, contour, and ornamentation.

B is the shank, projecting centrally from the back of the badge at a right angle. This shank B has its two ends a and b bent at right 35 angles, one end, a , extending along and soldered or otherwise secured to the back of the badge A and the other end, b , extending in the opposite direction and at a right angle with the shank B, all as plainly illustrated in Fig.

40 2. The end a of the shank B terminates in a sharp prong or point c , extending from the tip of the end a at a right angle thereto. The end b of the shank B has an aperture d , the shape of which is shown in Fig. 3, where it is

45 seen that said aperture has its opposite edges slightly approaching each other, as at e . A fastening-slide C has its outer (upper) end made with a curved lip f and its inner (lower) end made with a flange g , which extends therefrom at an angle. The width of the fastening-slide in relation to the other parts is indicated in Fig. 3 by the parallel dotted lines.

It is there seen that the flange g of the fastening-slide C exceeds in length the width of the aperture d , and therefore the ends of said flange g are slightly recessed to enable said flange g to overlie the part b of the shank B. The shank B has an opening through which the fastener C is inserted, as indicated in the sectional views, Figs. 2 and 5, and it is thus 60 evident that said fastener C is mounted slidably in position, because it is supported in said aperture of the shank B and by its flange g , which passes through the aperture d of the part b of the shank B, and is held thereto by 65 the overlying ends of said flange g .

In Figs. 4 and 5 the construction is slightly modified. Instead of having the part b of the shank B made with an interior aperture d and a closed outer end, as in Fig. 3, the parts $b'b'$ of the shank are spread apart, with curved ends turned outwardly, and there is a central opening d' , as shown in Fig. 4. In this case the fastening-slide C has the curved lip f , as before; but the flange g' is bent, as shown in 75 Figs. 4 and 5. The recessing of the flange g' is plainly seen in Fig. 4 at h . The slide C' is confined to a longitudinal movement and prevented from displacement, as already explained, by means of the curved lip f and the flange g' . As shown in Fig. 4, the edges of the opening d' approach each other, as at e' .

In attaching the badge to the garment the slide is moved to the position shown in Fig. 3, and the part with the slide thereon, as also 85 the central portion of the shank, which is at a right angle with the back of the badge A, is inserted through the buttonhole of the garment. As the back surface of the badge comes into contact with the face of the cloth the pin or 90 prong c of the part a penetrates the cloth, and so prevents the badge from any rotary or lateral movement when in wearing position. The fastening-slide C is then moved into the extended position shown in Fig. 2, thus 95 securing the badge in place.

The locking of the slide C in wearing position results from the narrowing of the aperture d of the part b of the shank B, as at e , Fig. 3, where the flange g is just of a size to 100 pass said narrow place of the opening with considerable frictional contact, as will be readily understood by an examination of Fig. 3. The same principle is involved in the

modified form of the device shown in Figs. 4 and 5. The spreading of the ends b' , as in Fig. 4, is useful as giving a wider contact of the fastening means with the back face of the garment, so tending to prevent any rocking or oscillating movement.

I claim as a novel and useful invention and desire to secure by Letters Patent—

1. The combination of a badge, a shank extending therefrom to the rear and provided with an aperture and bent at its outer end at a right angle, said end being also made with an aperture, and a slide mounted movably in the first-named aperture and having a flange extending therefrom at an angle and which passes through the second-named aperture, substantially as shown.

2. The combination of a badge, a shank extending therefrom to the rear and provided with an aperture and bent at its outer end at a right angle, said end being also made with an aperture, and a slide mounted movably in the first-named aperture and having a flange extending therefrom at an angle and which passes through the second-named aperture but provided with overlying ends, substantially as described.

3. The combination of a badge, a shank extending therefrom to the rear and provided with an aperture and bent at its outer end at a right angle, said end being also made with an aperture, and a slide mounted movably in the first-named aperture and having one end terminating in a curved lip and the opposite

end terminating in a flange extending therefrom at an angle and which passes through the second-named aperture but provided with overlying ends, substantially as specified.

4. The combination of a badge, a shank extending therefrom and provided with an aperture and having at one end a portion bent at an angle which is united to the back of the badge and terminates in a prong, and also having at its opposite end a portion bent at a right angle and extending in a direction opposite to the first-named portion and provided with an aperture, and a slide mounted movably in the first-named aperture and provided with a flange which passes through the second-named aperture, substantially as set forth.

5. The combination of a badge, a shank extending therefrom and bent at its outer end at a right angle, which bent end is provided with an aperture whose edges are provided with a cam-surface, a slide mounted movably on said shank and held to a longitudinal movement thereon by suitable means, and a flange extending from said shank and passing through said aperture and adapted to a sliding frictional contact with the cam-surfaces of said aperture, substantially as specified.

In testimony whereof I affix my signature in presence of two witnesses.

CHARLES A. RUSSELL.
